UNITED STATES PATENT OFFICE.

EMIL V. NOSER, OF ST. LOUIS, MISSOURI.

AEROPLANE.

1,287,083.

Specification of Letters Patent. Patented Dec. 10, 1918.

Application filed May 12, 1917. Serial No. 168,077.

To all whom it may concern:

Be it known that I, EMIL V. NOSER, a citizen of the United States, residing at the city of St. Louis and State of Missouri, have invented a new and useful Aeroplane, of which the following is a specification.

This invention relates to improvements in aeroplanes, and consists in the novel construction and arrangement of parts herein-
10 after more fully disclosed.

An object of the invention is to provide an aeroplane with sustaining planes arranged in collapsible form and adapted to open in a manner to prevent the sudden descent of
15 the machine.

Another object of the invention is to provide a machine of the character described with collapsible and extendible longitudinal central planes and lateral planes, whereby
20 when the machine ascends vertically air resistance is reduced, and when the machine starts to descend the planes open for supporting the machine.

Another object of the invention is to equip
25 a machine of the type described with elevating mechanism whereby the machine may ascend substantially vertically with power mechanism and controlling mechanism for driving said elevating mechanism.

Another object of the invention is to generally improve machines of the type mentioned in structural features in order to produce a light, durable and readily controllable machine.

With these objects, as well as other advantages and features of construction attainable from the invention, in view I have designed, arranged and combined the parts in the manner hereinafter more fully de-
40 scribed reference being made to the accom-
panying drawings, in which—

Figure 1 is a partial sectional plan view taken substantially on the line 1—1 of Fig. 2.

Fig. 2 is a vertical sectional view through
45 the machine taken substantially on the line
2—2 of Fig. 1.

Fig. 3 is a cross sectional view taken substantially on the line 3—3 of Fig. 1.

In the embodiment of the invention illus-
50 trated in the drawings, the main structure of the machine is shown as comprised of a sub-frame 1 and a super-frame 2 supported by uprights 3. The sub-frame is supported by a running gear 4. The machine is pro-
55 vided with elevating mechanism, adapted to raise the machine substantially vertical, in

the form of a casing 5 extending vertically from below the sub-frame to a point above the machine proper. Within the casing 5 is a driven shaft 6 which supports at its extremity a blade wheel 7, the shaft 6 being supported in suitable brackets 8 mounted within the casing 5.

The shaft 6 has gear connection 9 with a driven power shaft 10 which is operatively connected with a motor M by suitable two-speed gear transmission mechanism 11. A longitudinal shaft 12 supports at its rearward extremity a propeller wheel 13, the shaft 12 being designed for operative connection with the power shaft 10 by a three-speed gear transmission mechanism 14. Both of the transmission mechanisms 11 and 14 are controllable by a lever operated mechanism 15 and 16 respectively and by pedal operated clutch mechanism 17 and 18 respectively. The transmission mechanisms whereby the wheel 7 and the wheel 13 are driven are independently controllable so that the machine may be elevated independent of longitudinal propulsion, and vice versa.

The machine is equipped with a plurality of sustaining frames. In the embodiment shown there are two collapsible and expandible central planes and four collapsible and expandible lateral planes. The central planes each comprise two sections in the form of convex frames 19 pivoted at the center upon a rod 20 which rod is supported by standards 21 extending upwardly from the super-frame of the machine. The frames 19 are covered throughout with suitable material 22, preferably of tough fabric such as balloon silk, canvas and the like.

At the ends of the frame 19 are toggle lever struts 23 secured at one end to the underface of the frame and at the other end to a sliding collar 24 mounted over the standards 21. Centrally disposed with respect to the frame 19 and slidably mounted in brackets 25 supported by the main frame of the machine are rods 26. At either side of the rod 26 are additional toggle lever struts 27, the outer ends of which are connected to the frame 19 and the inner ends to sliding collars 28. Near the apex of the frame 19 on the rod 26 is a collar 29. Normally when the air pressure is on the exterior of the fabric covering 22 of the frames 19, said frames 110 collapse inwardly assuming the position shown in full lines in Fig. 3. The frames 19

remain in the collapsed position shown in this figure of the drawing during the vertical ascent of the machine. Whenever the machine tends to descend the air pressure on 5 the inner surface of the central planes will cause the frames 19 to open outwardly and the collar 28 to rise on the rod 26 until it abuts against the collar 29. The excess air pressure on the inner surface of the central 10 planes also raises the rods 26 upwardly, the upward movement of each of the rods 26 being limited by the abutment of the collar 30 carried by the rod adjacent to the lower end thereof abutting against the lower face of 15 the lower bracket 25. The lateral planes are arranged in pairs, the rearward pair associated with the rearward central plane and the forward pair associated with the forward central plane. While the lateral planes are 20 different in dimensions the structure of each is substantially the same.

Each of the lateral planes comprises a rectangular frame 31, the inner end of which is pivoted to the side member of the super- 25 frame of the machine. A longitudinal bar 32 is mounted to slide upon the end members of the frame. A spring roller 33 is supported by the side members of the super-frame and extend longitudinally at the inner side of the frame 31. A flexible curtain 34 is rolled upon the spring roller 33 and has its outer edge in connection with the sliding rod 32. Mounted upon and disposed at spaced intervals along the outer side member 30 of the frame 31 are rollers 35. Flexible connections in the form of heavy cord, wire or other suitable material, are attached at one end to the sliding rod 32 and extend downwardly over the outer edge of the frame 35 40 member passing over the rollers 35 and are connected at their opposite end into a clevis 36 on the end of the rod 26.

An expandible link comprising a tube 37 and a rod 38 constitute a support between 45 the frame of the machine for each of the frames 31. The rod 38 has its outer end attached to the outer side member of the frame 31 and telescopes into the tube 37 having pin and slot connection 39 therewith. The inner 50 end of the tube 38 is pivoted to the bracket 25 supported by the main frame of the machine.

Normally when the machine is ascending and the central planes are collapsed the lateral planes will likewise be collapsed and the flexible curtains 34 raised on the frames. When the central planes are elevated and the rods 26 thereby raised the flexible curtains 34 are pulled downwardly so as to 55 cover the full area of the frames 31, the air pressure of the inner face of the lateral planes carrying the planes outwardly to the position shown in dotted lines in Fig. 3. Thus it will be observed that the central planes 60 and the lateral planes are coordinated so

that upon the aeroplane tending to descend the supporting surface of both the central planes and the lateral planes will be increased by the adjustment thereof, and that when the machine ascends both the central 70 planes and the lateral planes will be in a collapsed position affording a minimum of resistance to the vertical ascent of the machine.

I am aware that the principles of the invention may be embodied in other forms, and I do not limit myself to the construction shown and described, but what I claim and desire to secure by Letters Patent, is:—

1. In an aeroplane, the combination with 80 a main body composed of a sub-frame and a super-frame, a vertical and a horizontal propeller for elevating and propelling the main body, a motor, independent gear change mechanism for independently driving said vertical and horizontal propeller, collapsible centrally located planes carried by the super-frame, a plurality of lateral planes each having a movable curtain therefor, and connections between said movable 85 curtains and the central planes, whereby the curtains are moved to fully cover the lateral planes when the aeroplane tends to descend.

2. In an aeroplane, the combination with 90 a main body, a central plane comprising collapsible covered frames pivoted on a support extending axially of the machine, and toggle lever struts connected to each of said frames, a sliding rod supported by the main frame of the machine and connected with 100 said central planes, a pair of laterally extending planes pivoted to the main frame, a roller curtain adapted to cover each of said lateral planes, and connections between said rod and said curtains whereby, when the central plane and the lateral planes extend, the curtains will be drawn to cover the lateral planes.

3. In an aeroplane, the combination with 110 a main frame, of a suspending plane comprising a frame pivoted to the main frame, a movable roller curtain mounted at the inner side of the frame, connections with said curtain whereby, when the frame extends laterally, the curtain will be drawn 115 over the frame and when the frame is collapsed the curtain will be rolled from a portion of said frame.

4. In an aeroplane, the combination with 120 a main frame, lateral sustaining planes comprising frames pivoted to the side members of the main frame, collapsible links attached at one end to the main frame of the machine and at the other end to the frames respectively, a slidable curtain for each of 125 the frames, and means for moving said curtains to cover and uncover said frames.

5. An aeroplane, comprising a main body, a pair of collapsible central planes and a plurality of lateral planes, slidable curtains 130

for covering said lateral planes, and connections between said lateral planes and said central planes for moving the curtains covering the lateral planes.

- 5 6. In an aeroplane, a main body, a central plane running longitudinally of the main body and supported above the same comprising a pair of collapsible covered frames, a vertically slidable support for
 10 said frames, a pair of lateral planes arranged on either side of said central plane and pivoted to the main frame of the machine, a roller curtain for each of said lateral planes, a sliding rod mounted in each
 15 of said lateral planes and connected with the outer ends of said curtains respectively, flexible connections between said rods and the slidable rod for the central planes, whereby when said central plane is ex-
 20 tended and elevated the curtains will be drawn to cover the lateral planes.
7. An aeroplane, comprising a main frame composed of a sub-frame and a super-frame, running gear for supporting the frame, two
 25 central planes arranged longitudinally of the main frame comprising collapsible frames, a double pair of lateral planes ar-

ranged one at each side of said central planes respectively, said lateral planes being pivoted to the side members of the super-frame, an adjustable cover for each of said lateral planes, and a connection between the central planes and the respective pairs of lateral planes, whereby the movable covering for the lateral planes is adjusted by the movement of said central planes.

8. In an aeroplane, the combination with a main frame, a central plane composed of collapsible leaves movable vertically, lateral planes supported at each side of said central planes having supporting links connected with the lateral planes and with the main frame, an adjustable curtain for covering each of said lateral planes, flexible connections connected with the adjustable curtain and extending over the outer edge of the planes and connected with the support for the central plane, whereby when said central plane is elevated the curtains of the lateral planes will be adjusted to cover the surface thereof.

In witness whereof I have signed this specification.

EMIL V. NOSER.
